UNITED STATES PATENT OFFICE

ERIC S. CARLSON, OF DETROIT, MICHIGAN, ASSIGNOR TO TERNSTEDT MANUFACTURING COMPANY, OF DETROIT, MICHIGAN, A CORPORATION OF MICHIGAN

DESIGN FOR A WINDOW-REGULATOR HANDLE OR SIMILAR ARTICLE FOR AN AUTOMOTIVE VEHICLE

Application filed November 13, 1930. Serial No. 37,642. Term of patent 7 years.

To all whom it may concern:

Be it known that I, ERIC S. CARLSON, a citizen of the United States, residing at 765 Central Avenue, Detroit, in the county of Wayne and State of Michigan, have invented a new, original, and ornamental Design for a Window-Regulator Handle or Similar Article for an Automotive Vehicle, (Case B), of which the following is a specification, reference being made to the accompanying drawings, forming part thereof.

Fig. 1 is a front elevation showing my new ornamental design for a window regulator handle or similar article for an automotive vehicle.

Fig. 2 is a side elevation of the same.

I claim:

The ornamental design for a window regulator handle or similar article for an automotive vehicle substantially as shown.

ERIC S. CARLSON.
